UNITED STATES PATENT OFFICE

CARL FRIEDRICH ERN, OF SOLINGEN-WALD, GERMANY

SAFETY DEVICE FOR RAZOR BLADES

Application filed December 3, 1931, Serial No. 578,759, and in Germany August 26, 1930.

The invention relates to a safety device for razors which comprises a yoke member which can be positioned on the blade to embrace both sides thereof.

5 The known safety devices of this kind for razors do not satisfy in practice the various requirements which have to be met.

Known devices in part utilize a protective sheet which is positioned over the blade on 10 one side only so as to extend close to the cutting edge and is secured to the back of the blade in various ways all of which are to a greater or less extent inconvenient. Such devices do not ensure an adequate margin of safety against damage.

With the object of attaining a greater degree of safety, other proposals have included a yoke member which is adapted to be positioned on the blade and embraces it, extending almost to the cutting edge on both sides.

As compared with the safety devices extending on one side only such devices are expensive to manufacture particularly the 25 parts of the yoke are resiliently connected together for the purpose of clamping the yoke on the back of the plate. In addition the requisite rigid mounting on the blade depends on the efficiency of small springs 30 or the like which weaken after being in use for a greater or less time. Also it is not altogether simple to clean and dry such devices as a cloth or the like can only be inserted between the limbs of the yoke with difficulty 35 and moisture and dirt readily collect in the screw threads, the hinges and the like. In this way not only is a rapid decomposition assisted but the risk of infection during shaving is also involved.

40 It is the object of the present invention to remove all these disadvantages and to provide an efficient and simple construction of a safety device. With this object in view the invention provides a safety device which 45 comprises two independent members adapted to be clamped to the back of the razor blade, each of said members extending adjacent to one side of the blade. Further features of the invention may be seen from the following specification having reference to the

accompanying drawing in which one embodiment of the invention is shown by way of example.

Figs. 1 and 2 show side elevation and end elevation respectively of one half of the yoke 55 of the safety device.

Figs. 3 and 4 show side elevation and end elevation of the other half of the yoke.

Figs. 5 and 6 show the safety device positioned on a razor blade, one part of the yoke 60 being shown in front in Fig. 5 and the other part in Fig. 6.

Fig. 7 is a cross section through the construction corresponding to Figs. 5 and 6.

Fig. 8 is an enlarged cross sectional view 65 of a razor blade equipped with the safety device according to the invention.

The present invention resides in that the yoke consists of two halves consisting of independent constructional units which are 70 connected together and with the back of the blade in that one half of the yoke or one yoke member clamped directly on the back of the blade by means of a clip-like portion and the second half of the yoke is provided with a 75 similar clip-like portion enabling it to be secured in position by sliding it telescopically over the other yoke member. The yoke device thus obtained is particularly simple in construction and consequently is also very 80 cheap to manufacture. Moreover it is capable of being both quickly and adequately cleaned.

The safety device comprises two sheet steel members *a* and *b* constituting the two halves 85 of the yoke which are adapted to be positioned in superimposed relationship on the back of the blade. Each half of the yoke *a* and *b* is of the same length as the blade of the razor and a sleeve open on one side is formed on one longitudinal edge by bending. The sleeve *c* of the half *a* is so constructed 90 that it fits closely on the back of a razor blade with the flat part of the yoke member extending approximately parallel to the blade in close proximity thereto. The sleeve *d* of the yoke member *b* is such that it fits closely 95 on the sleeve *c* of the member *a* and when the yoke member *b* is positioned the flat part also lies parallel to the blade in close proximity thereto on the opposite side to the yoke mem- 100

ber *a*. The sleeves *c* and *d* are mounted on the back of the blade and on each other in such manner that they cannot rotate about the back of the blade.

- 5 The degree of safety afforded is particularly great if the two yoke members terminate in edges spaced laterally by a small distance from the cutting edge. In a preferred arrangement presently to be described, this
 10 effect is attained in that the two halves of the yoke are each folded back at the free edge and the folded back edge strip terminates at some distance from the edge in a turned up flange. This arrangement also affords the advantage
 15 that the edges of the safety device are strengthened and thus a bending of the entire edge or of individual teeth is prevented.

In this arrangement the edges of the other longitudinal side of the two yoke members
 20 *a* and *b* are folded back on the side on which the sleeves *c*, *d* are open and by bending is formed into a low flange *e* projecting from the yoke member. The flanges *e* rest against the sides of the blade of the razor and ensure
 25 the positioning of the yoke members at the permissible least distance from the blade. The blade is thus spaced from the edges formed by bending which constitute effective protective edges *f* and *f'* respectively. These
 30 edges are serrated in known manner.

The yoke member *a* is not so deep as the yoke member *b*, in accordance with known constructions. By this arrangement it is attained that the cutting edge of the blade projects beyond the protective edge *f* of the yoke member *a* whereas the protective edge *f'* of the yoke member *b* projects beyond the cutting edge of the blade. Further the yoke members are so dimensioned that the two
 40 protective edges *f* and *f'* and the cutting edge of the blade lie in a straight line or in a plane, in known manner. The obliquity of this line or plane to the blade corresponds to the obliquity of the latter to the skin in shaving. Thus on either side of the cutting edge of the blade the skin is supported by the protective edges of the yoke members *a* and *b* in such manner that it is impossible to cut or damage the skin.

50 I claim:—

1. A safety device for a razor blade, comprising a strip-like guard to cover one side of the blade nearly to the edge of the blade, said guard having a sheath-like portion
 55 adapted to grip the back of the blade, another strip-like guard to cover the other side of the blade projecting beyond the edge of the blade, said other guard being adapted to grip the back of the first-mentioned guard,
 60 both strip-like guards being of such a length as to lie substantially with the edge of the blade in one plane; both strip-like guards having projections to form a support against the blade, and to space them therefrom.

65 2. A safety device for a razor blade com-

prising two independent yoke members, a clip-shaped portion on one of said members enabling it to be clamped to the back of the blade to extend over one surface thereof, a clip-shaped portion on the other of said members enabling it to be clamped to the back of the blade to extend over the other surface thereof by embracing the clip portion of the first member clamped thereon and a flange projecting inwardly from each of said members to engage the surface of the blade for spacing said members from said blade in the vicinity of the cutting edge.

In testimony whereof I have signed my name to this specification.
